 General Motors Corporation, Detroit, Mich., a
 corporation of Delaware

Application February 23, 1938, Serial No. 191,866

6 Claims. (Cl. 175—315)

This invention relates generally to the manufacture of electrical condensers, and particularly to electrolytic condensers, having to do with the formation of condenser sections or bodies with integral terminal attaching portions, and a method for constructing the same.

It is one of the objects of this invention to provide a condenser body or section with integrally formed terminal attachment portions, without involving an undue waste of electrode material.

Another object of this invention is to provide a compact condenser section with terminal attaching portions without material reduction of capacity of the completed unit for the quantity of the electrode material used.

Another object of the invention is to provide an integrally formed terminal attaching portion for a convoluted electrode strip, by the use of a minimum of electrode material.

Another object of this invention is to provide a terminal union for a condenser section without introducing the possibility of galvanic action and/or anodic corrosion.

Another object of the invention is to provide a method for manufacturing condenser sections with the least amount of labor and time consumed, and with a substantial saving of material, thereby reducing the ultimate cost of the condenser section.

Another object of the invention is to provide a method of manufacturing condenser sections whereby terminal attaching portions of suitable characteristics may be formed coincident with the winding of the electrodes and spacers, and without adding to the cost of manufacture.

Further objects and advantages of the present invention will be apparent from the following description, reference being had to the accompanying drawing wherein a preferred embodiment of the present invention is clearly shown.

In the drawing:

Fig. 1 is a schematic showing illustrating one step in the formation of a condenser section according to the present invention.

Figs. 2 and 3 illustrate other and succeeding steps in the formation of the condenser section shown in Fig. 4.

Fig. 4 illustrates one form of a completed condenser section, with alternative means for attaching a terminal member.

In the manufacture of electrical condensers, the major problem in the use of very thin electrode material in conjunction with spacers in convoluted form, consists in establishing a dependable and inexpensive connector between the electrodes and the condenser terminals. The conventional folding of the ends of the foil or electrode material in the shape of a tab has the drawback of using up a very long strip of the electrode material for the purpose of preparing the tabs.

Since the thin foil requires many layers, sometimes 20 or 30, in order to insure a mechanically strong terminal connector, there is thus used a considerable portion of material for tab formation that does not enter into the condensing function of the unit. Such a great number of layers requires the use of a substantial portion of the total length of the electrode material in making the terminal connections, and this means a considerable waste of material, that is, of both electrode material and spacer material. Furthermore the folding of the electrode material into 20 or 30 layers requires extra labor and time which adds to the cost of manufacture of the condenser section.

Another problem in the use of strip material in convoluted form, particularly with condensers used in radio, is the impedance to high frequency circuits. The successive turns of the electrodes act to induce currents in the opposite direction, which becomes of great moment in radio circuits, or where circuits of high frequency obtain.

In overcoming these difficulties and objections, I accomplish the stated and other objects by forming the terminal attaching portions of the electrode material coincident with the first few turns in the process of winding the electrodes and spacers. In accomplishing this, I draw the strips of the electrode material and spacers from the supply rolls, and dispose their ends on the winding mandrel such that the two spacers are centered in the desired manner for the completed winding, and with the strips of electrode material each laterally displaced or offset so as to have an edge portion extending beyond the edge of the centered spacers. With the strips so adjusted, I wind the materials into a cylindrical or tubular body having the desired amount of material for the capacity contemplated. While the strips are being wound, and during the first few convolutions thereof, I cause the electrode strips to gradually readjust themselves to a substantially centered relation with respect to the spacers, and thereafter continue the winding with all of the strips respectively centered or in aligned relation. By winding the strips in this form, I produce at each end of the tubular body a conical spiral of exposed electrode material, which forms a convenient attaching portion for a lead or terminal member, as the case may be, having a most efficient electrical connection with the body or active portion of the respective electrodes. To these exposed electrode portions, I attach my leads or terminals by either welding or by riveting. On the other hand, I may make use of the electrode extensions as connectors by securing them directly to a terminal member carried by an insulator closing the casing, where they may be adopted as an exterior terminal.

With particular reference to the drawing, 10 ill- 60

illustrates a mandrel, upon which the condenser sections are to be wound, and which is driven by means of a shaft 12. A loose assembly or pile of condenser material to be wound is drawn from the supply rolls and is adjusted upon the mandrel 10, the pile of materials comprising a first spacer 13, a first electrode strip or foil 14, a second spacer 16, and a second electrode strip or foil 18. These strips are generally centered and piled in alternate order in that there is a spacer against which is an electrode strip, which in turn is covered by a second spacer, and on top of which is a second electrode strip. The spacers are of greater width than the electrode strips, so that in case of accidental displacement of the electrode strips there will be little or no likelihood of a short circuit between them.

As illustrated in Fig. 1, after drawing these condenser strips or foils over the mandrel, I leave the spacers 13 and 16 centered therewith, but I displace the foil 14 to the left so that it extends beyond the edge of the spacer 12 as indicated at 20. The electrode strip 18, I likewise displace to the right as indicated at 22. It will be noted that though the ends of the electrodes 14 and 18 are offset, they are slightly out of parallel, and in fact having an appreciable taper toward the supply rolls. This is because the supply rolls are centered for the purpose of providing an assembly of strips that are substantially centered.

With the condenser strips so adjusted, I rotate the mandrel 10 through a certain number of revolutions to wind the condenser section to the desired capacity. During this rotation of the mandrel the pile of condenser strips will be wound upon the mandrel in tubular form having a central opening equal to the cross-section of the mandrel; and the displaced or offset electrode strips will rapidly but gradually assume a centered relation with respect to the spacers, which coincidentally forms a suitable terminal attaching portion at each end of the condenser section while the section is being wound to capacity, and with no further attention given to it than the initial offsetting or displacing of the ends of the electrode strips at the time that the strips are being attached to the mandrel preparatory to winding.

The condenser section thus far formed, provides a hollow cylindrical or tubular section, characterized by exposed electrode portions at each end thereof. In further manipulating this winding toward the ultimate end, I may collapse or substantially flatten the tubular section into a form comparable with the illustration of Fig. 2, in which there is at least one thin portion 30, and in which the central passage of the condenser section has been practically done away with, or the opposite surfaces of the passage brought into substantial engagement as indicated at 32. This forms what may be called a wafer or a packet of condenser material, and is generally indicated at 34. As indicated in Fig. 2, the complete flattening or collapsing of the tubular portion provides the two thinned portions 30 and 36 connected by the plane portions 38 and 40. While I have illustrated the completely collapsed form, as shown in Fig. 2, I contemplate any other collapsing of the tubular portion such as one of tear-drop or non-symmetrical cross-section, or one in which but a single thinned edge 30 is formed, and which involves substantially a fold

of the strips transverse to their length, or across their convolutions.

A further step in completing the formation of the condenser section may involve rolling the packet or wafer upon itself, such as by starting with the thinned edge 30 and bending up and rolling it over tightly, or in substance folding the edge 30 against the plane portion 40, after which the remainder of the packet is wrapped around the edge portion 30 to complete the bundle 10 of condenser material substantially as illustrated in Fig. 3, and indicated at 42. This step results in a generally rounded bundle of inter-leaved and alternating strips of spacer and electrode material arranged generally in a contour simulating the capital letter G, or otherwise in which the several strips have a curved extent from beginning to end, comprising the reverse turns as indicated at 44, 46 and 48.

The resulting body from these steps is illustrated in Fig. 4 in which the bundle 42 provides the exposed electrode extensions 20 and 22, comprising conical spirals of the exposed electrode material adapted for terminal attachment. In attaching connectors or terminal leads to the 25 terminal attaching portions 20 and 22, I do so in a manner to eliminate galvanic action and/or anodic corrosion which is likely to occur in the instance of the electrolytic condensers, if use is made of dissimilar metal or of non-filming 30 metals. After the bundle 42 is formed, I pinch together the overlapping convolutions of the exposed electrode extensions, and then either weld the conductor 44 to the flattened and compacted electrode edges, as indicated at 46, or else I attach the lead 44 by means of a hollow rivet 48, passing through the exposed electrode edges as indicated at the right in Fig. 4. I prefer to use leads and rivets of the same film forming metallic content as that of the electrode material, thereby preventing the occurrence of any galvanic action and/or anodic corrosion between or at the junction of either the electrode material, the leads or the attaching means. If the leads were to be soldered or otherwise affixed by any similar 45 means, that involves the use of dissimilar metals galvanic action or anodic corrosion is likely to be manifest.

Thus, in manufacturing condenser sections, I provide a method of procedure in which I arrange 50 electrode or foil strips on a mandrel with the spacers and the foils or electrodes initially displaced or offset, and spirulate or wind the strips in convoluted form, during which the electrode strips become properly centered or substantially 55 directly superimposed in relation to the spacers. After this I flatten the tubular or cylindrical form thereby presenting a flattened body, which flattened form I cause to be again spirulated or wound, to provide a compact bundle in which 60 the strip or layers are each reverse curved, and any internal spacing substantially done away with. To the exposed margins of the electrode material of this compact bundle, I affix appropriate connecting means by either welding or 65 riveting.

It will be noted that each of the electrode strips at the start of the winding, forms a conic spiral telescoped portion extending beyond the edge of the spacers, in which portion the successive convolutions of the electrode material are in contacting engagement, so that when pressed together incident to welding or riveting the connector or lead thereto the successive convolutions are brought into electrical conductivity at 75

their edges, thereby eliminating the induction function of those convolutions so connected by the bond. That tends to reduce the impedance of the electrode strip so bonded, the closer to the end of the edge of the spacer the lead attachment is made, the greater number of electrode convolutions that are bonded, and consequently the greater the reduction in impedance. In practice I may telescope either both of the electrode strips, or I may telescope but one of the strips, and I may pinch the exposed electrode edges and attach the connecting lead at any point in the process of formation of the section. That is to say, I may connect the electrode edges with the lead, just after the body is removed from the mandrel, or I may connect the lead to the electrode edges just after the hollow cylinder has been flattened to the form shown in Fig. 2. Obviously I may adopt the condenser body with the attached leads, in either instance without pursuing the subsequent steps described hereinabove. In other words, I may elect in some instances to use the hollow cylinder with attached leads and without flattening, as the form to be assembled, or I may elect in other instances to use the flattened form with attached leads and without the second rolling as the form to be assembled. Though contemplation is had of those forms, it is preferred to form the spirulated body into the compact form illustrated and claimed, since the available mounting space is usually limited, especially in radio installations.

The resulting article of manufacture is one in which the electrodes and spacers are in compact form and is encompassed within small physical dimensions. The foil margins or electrode members are telescoped in the course of winding sufficiently to establish a connector integral with the electrode itself. It is found in practice that some 6 to 10 convolutions at the start of the winding are sufficient to provide the necessary material to provide a satisfactory connection. The number of initial convolutions necessary to form a connection will depend upon its ultimate desired length, and will take into account whether leads or connectors are to be attached to the exposed portions of the electrodes as illustrated, or whether the integral connectors resulting from the telescoping of the electrode material, are to be brought out of the container and secured to the terminal on the outside of the casing. If the latter procedure is to be followed it may be necessary to wind more than 10 convolutions in offset relation. If the integral connectors are to be joined to leads inside the casing there may be required less than 6 initial offset convolutions.

While the embodiment of the present invention as herein disclosed, constitutes a preferred form, it is to be understood that other forms might be adopted, all coming within the scope of the claims which follow.

What is claimed is as follows:

1. The process of making electrolytic condensers from electrode strips of uniform width, comprising the steps in combination, offsetting the start ends of electrode strips relative to spacer strips, spirulating the electrode strips with spacer strips into a hollow cylinder while readjusting the electrode strips to substantially centered relation with each other and with the spacer strips, collapsing the cylinder, and spirulating the resulting body through substantially a complete whorl.

2. The process of making electrolytic condensers having electrodes of uniform width and spacers of greater width in convolute relation, comprising the steps in combination, laterally displacing the ends of electrode strips for the first convolution so that each electrode strip projects at one edge beyond a spacer edge, and decreasing the displacement for each successive convolution until the strips of electrode material and spacers are directly superimposed in centered relation, and continuing with successive convolutions until the desired capacity is attained.

3. The process of making electrolytic condensers having electrodes and spacers in convolute relation, comprising the steps in combination, selecting electrode strips of continuously uniform width and spacers of greater width and arranging them in alternating superposed relation with their ends on a winding mandrel, offsetting the ends of the electrodes beyond the opposite edges of the spacers at the start of the convolutions to provide terminal attaching portions, spirulating the offset electrodes with interposed spacers into a substantially hollow cylinder, and rapidly decreasing the offset of the electrodes for the first few convolutions until the electrodes are substantially centered and have their edges in alignment and thence spirulating the superimposed electrodes and spacers to effect the desired capacity.

4. The process of making electrolytic condensers having electrodes and spacers in convolute relation, comprising the steps in combination, shifting the starting ends of the electrodes laterally beyond the edges of the spacers, spirulating the electrodes and spacers and coincidentally drawing in the electrodes toward a common centered position to rapidly eliminate the initial shift for the bulk of the convolutions, thence spirulating the electrodes and spacers in centered relation to form a hollow cylinder of the desired capacity, flattening the cylinder to form a thin edge across the body transverse to the convolutions, spirulating the flattened body by rolling the thin edge innermost, and thence securing terminal leads to the shifted portions of the electrodes.

5. The method of making condenser sections from narrow electrode strips of uniform width interleaved with spacers of greater width comprising the steps in combination, centering the start ends of the spacer strips on a winding mandrel, offsetting the start ends of the electrode strips so as to expose an edge of each electrode on each side of the centered spacer strips and so that the electrode strips converge at a point remote from the mandrel where the electrode strips and spacer strips are all centered, thence winding and coincidentally centering all of the strips.

6. The method of forming condenser sections, comprising the steps in combination, adjusting a pair of spacers in centered relation on a winding mandrel, adjusting a pair of electrode members so that at least one electrode member is exposed at its edge beyond the edge of the spacers, and so that the edge of the electrode is out of parallel with the edge of the spacers, and converges toward the center line of the spacers at a point remote from the mandrel, and winding the spacer and electrode strips on the mandrel while recentering all of the electrode strips and spacer strips.
